UNITED STATES PATENT OFFICE.

GUSTAV O. WILMS, OF MILWAUKEE, WISCONSIN, ASSIGNOR TO THE RELIANCE COMPANY, OF MILWAUKEE, WISCONSIN, A CORPORATION OF WISCONSIN.

DESIGN FOR A SWITCH-BOX COVER.

Application filed March 1, 1928. Serial No. 25,639. Term of patent 14 years.

To all whom it may concern:

Be it known that I, GUSTAV O. WILMS, a citizen of the United States, residing at Milwaukee, in the county of Milwaukee and State of Wisconsin, have invented a new, original, and ornamental Design for Switch Box Cover, of which the following is a specification, reference being had to the accompanying drawing, forming part thereof.

I claim:

The ornamental design for a switch box cover, as shown.

GUSTAV O. WILMS.
